UNITED STATES PATENT OFFICE

ALFRED SCHOELLER, OF FRANKFORT-ON-THE-MAIN, GERMANY

CARBURETOR

Application filed September 20, 1927, Serial No. 220,723, and in Germany September 27, 1926.

This invention relates to carburetors in which the fuel-supply is regulated by means of a baffle-plate exposed to the suction-draft of the air.

5 This invention has for its object to neutralize a number of disturbing influences which make it difficult or impossible to equalize the quantity of outflowing fuel with the fuel-consumption of the motor or with the 10 quantity of air flowing through the carburetor.

As the air-draft passing through the carburetor is not produced by a source of power acting constantly but by reciprocating pistons which suck in the air in jerks it is unavoidable, even if there are a great number 15 of pistons which are staggered, that also the discharge device, operated by the baffle-plate, vibrates. The vibrations are not prejudicial 20 unless the average stroke of the fuel-discharge-valve be disturbingly influenced by resonance or interference.

Anyone skilled in the art knows that in connection with fuel discharge-valves which 25 are lifted more or less by baffle-plates, buffer-springs and similar devices have to be used which are however arranged so that they distort and displace the oscillating amplitude, but do not make the same harmless in a sufficient 30 degree.

According to the invention the fuel-discharge valve is loosely arranged between the arm of the baffle-plate bearing from below and the pressure-bolt of the counter spring 35 of the valve, bearing from above, merely the pivot-axe of the baffle-plate having a damping-means which acts uniformly towards both sides and produces always only a temporary counter-pressure. From this arrangement result three oscillating systems, i. e. (1) the baffle-plate, (2) the valve-body and (3) the spring-controlled pressure-bolt of the valve, so that formation of resonances and interferences is made difficult. Special- 40 ly by the arrangement of the damping means of a baffle-plate and by a separation of the baffle-plate from the valve, a great portion of the disturbing movement is made ineffective from the beginning. It is important 45 that the damping-means produces always 50

only a temporary counter-pressure and has not a shock accumulating effect.

A further impeding of the uniform discharging of the fuel from the discharge-valve is due to the pressure-differences 55 formed in the carburetor-channel around the baffle-plate. By the suction-draft from the engine a conversion of speed into over-pressure is produced underneath the baffle-plate, and behind the baffle-plate a suction-vortex 60 is produced. This suction-vortex has an effect upon the fuel-valve which cannot be calculated and, according to the invention, it is rendered ineffective by the arrangement underneath the valve-disk of the fuel-valve of 65 one or several air-channels communicating with the atmosphere. As, however, by all these means an occasional excess of outflowing fuel cannot be avoided so that there will remain a remainder of liquid, a cavity is arranged underneath the fuel-valve by which the fuel in excess is distributed over a large 70 surface in the carburetor-channel, where it is consequently consumed in a short time. When the front-edge of the cavity is close to 75 the lower edge of the throttle valve the advantage is obtained that the valve moves from the closed position into the open position very readily and offers in the open position a good discharge path for the air. 80

An embodiment of the invention is illustrated by way of example, in the accompanying drawings in which

Fig. 1 shows the carburetor in longitudinal section.

Fig. 2 shows the baffle-plate viewed in the direction of the arrow A Fig. 1.

Fig. 3 is a side-elevation of the carburetor, the damping-arrangement being shown in section.

Fig. 4 is a top plan view of the carburetor.

The carburetor-channel 1 can be opened in the direction towards the sucking piston of the engine to any degree with the aid of the throttle-valve 2. The engine is connected to the flange 26, the air admission taking place at 27. A baffle-plate 3, known per se, is lifted by the suction-draft and lifts, by means of its arm 4 standing at an angle to said baffle-plate, the fuel valve 5. On the fuel-valve 5

rests loosely a bolt 6, controlled by a valve-counter-spring 7. On the axle 8 of the baffle-plate 3 an arm 9 is mounted at an angle outside the channel 1 as shown in Figs. 2 to 4, said arm engaging at the centre of gravity with a piston-body 10. The piston-body 10 is guided in a cylinder 11 which has at the middle apertures 12. The cylinder 10 has in its inner surface narrow flutes permitting the flowing out of the air which is compressed in the spaces 13. The damper-arrangement 9 to 13 of the baffle-plate opposes consequently a certain resistance at jerk-like displacements, but never a counter-force capable to exert any influence upon the adjusting of the throttle-valve with regard to a constantly acting suction-draft.

Owing to the arm 4 of the axle 8 of the baffle-plate 3 standing at an angle and resting loosely on the valve-body 5 the oscillating system of the baffle-plate 3 is absolutely separated from the oscillating system of valve 5. As further the bolt 6, controlled by the spring 7, rests loosely from above on the valve 5, this valve 5 is influenced as little as possible by the oscillations of the surrounding elements for providing an open passage. Air-channels 14, communicating with the atmosphere serve to render harmless for the fuel flowing out through valve 5 any suction-vortex which might be produced behind the baffle-plate 3. In the bottom-plate of the carburetor a cavity 15 is arranged, designed to receive excessive fuel so that this fuel cannot be distributed over too large a surface of the carburetor channel where it would be consumed in a short time and generally for no useful purpose.

On the shaft 19 of the throttle-valve 2 an angle lever 24 is further arranged, the end 25 of which is connected with a push rod 20 bearing against a lever arm 21 on the shaft 8 of the flap valve 3. The other end 18 of the angle lever 24 extends into the range of the cam 17 of a lever system 16 adapted to be operated from the driver's seat. As soon as the throttle-valve 2 has been moved by the lever system 16 into the widest open position, the end 25 of the angle lever 24 pushes the push rod 20 to the right, said push rod lifting by means of the lever arm 26 the axle 4 of the flap valve 3 a short distance opening thereby the fuel valve, so that the quantity of fuel necessary for the starting of the engine can drop into the cavity 15. The push rod 20 does not impede the flap-valve 3 from sufficient oscillating at the full admission period. 22 is an explosion flap arranged on the flap valve 3 so that it can freely oscillate in the direction towards the air admission and designed to prevent that at back firing from the engine a deformation or destruction of the elements occurs.

I claim:—

65 1. A carburetor comprising in combination

70 a casing having a mixture chamber provided with an air inlet and a mixture outlet, a fuel inlet valve discharging in said mixing chamber, a pivotally mounted flap valve adapted to be operated by suction, an inclined arm fixedly mounted on the pivot of said flap valve and adapted to control the opening of said fuel valve and movable independently thereof, and a dash pot arrangement for said flap valve mounted on the outside of the said casing and completely out of communication with the interior of the casing and being adapted to retard uniformly in either direction the opening of said flap valve.

75 2. A carburetor as specified in claim 1, in which said inclined arm of the flap valve loosely bears from below against said fuel inlet valve, a bolt loosely bearing from above on said fuel inlet valve, and a valve counter spring acting on said bolt.

80 3. A carburetor as specified in claim 1, comprising in combination with the fuel inlet valve the flap valve and the casing of said fuel inlet valve, a bottom plate of said casing having a cavity under said fuel inlet valve 85 in proximity to the lower edge of said flap valve and adapted to collect excessive fuel and to facilitate the flow of air underneath said flap valve.

85 4. A carburetor as specified in claim 1, comprising in combination with the flap-valve, a throttle-valve in the entrance of said carburetor, a lever positively connected with said throttle-valve, and means for transmitting the movement of said lever upon said flap-valve to make, when said throttle valve is completely opened, said flap-valve oscillate a sufficient degree for starting the engine, said means having such short useful length that said flap-valve can further oscillate at full 90 admission period.

95 5. A carburetor as specified in claim 1, in which an explosion flap-valve is freely oscillatable in a direction opposite the direction in which the air flows so that at an explosion the 100 gases from combustion can freely flow to the outer side.

105 In testimony whereof I affix my signature.
ALFRED SCHOELLER.
